UNITED STATES PATENT OFFICE.

JOHN CRAWFORD, OF SEATTLE, WASHINGTON.

FUEL-FEEDING APPARATUS.

No. 831,145.

Specification of Letters Patent.

Patented Sept. 18, 1906.

Application filed August 17, 1905. Serial No. 274,585.

To all whom it may concern:

Be it known that I, JOHN CRAWFORD, a citizen of the United States, residing at Seattle, in the county of King and State of Washington, have invented certain new and useful Improvements in Fuel-Feeding Apparatus; and I do hereby declare the following to be a full, clear, and exact description of the same, reference being had to the accompanying drawings, forming a part of this specification, and to the letters of reference marked thereon.

The present invention relates to apparatus for feeding fuel to furnaces, and more especially to apparatus for continuously feeding relatively fine and cheap grades of fuel, as pea, buckwheat, or screenings of coal, although the apparatus is well adapted for feeding fuel of higher grades, especially where the fuel is reduced to a small size, either intentionally or by reason of previous handling.

The object of the invention is to improve the apparatus or appliances by which the fuel is fed into the furnace and distributed over the grate, whereby a more even distribution is secured and a more thorough and effective commingling of the fuel with the oxygen-supplying fluid is effected without the necessity of employing mechanical means for effecting the admixture and projecting the fuel into the furnace.

The invention consists, primarily, in a pair of hinged or pivoted distributors adapted to be oscillated vertically about their axes in substantial parallelism and between which the fuel is admitted in position to be ejected by an impelling medium—such, for instance, as air under pressure, ordinary steam, or superheated steam.

The invention further consists in the employment of distributing means movable to direct the fuel nearer to or farther from the front of the furnace in connection with a spreader or duct for admitting superheated steam or other elastic medium under pressure, said spreader being movable with the distributing means, whereby it will effect the projection of the fuel at a substantially uniform angle with relation to the distributing means.

The invention further consists in a distributing means for the fuel in connection with a spreader for admitting steam or elastic medium under pressure, said spreader having its discharging-apertures extending around the fuel-supply passage from side to

side, whereby the fuel will be projected by said medium in radial lines.

The invention further consists in certain novel details of construction and combinations and arrangements of parts, all as will be hereinafter described, and pointed out particularly in the appended claims.

Referring to the accompanying drawings, Figure 1 is a front elevation of a portion of a steam-boiler furnace embodying the present improvements. Fig. 2 is a vertical section, partly in elevation, of the structure illustrated in Fig. 1. Fig. 3 is a detail plan view of the lower distributor-plate, showing the preferred arrangement of spreader. Figs. 4 and 5 are views similar to Fig. 3, showing modified arrangements of the injector-pipe or spreader. Figs. 6 and 7 are detail vertical sections showing a modification of the distributor mechanism.

Like letters in the several figures indicate the same parts.

The furnace itself may be of any preferred or well-known construction, and consequently it is not deemed necessary to illustrate details of construction. In said drawings, however, the front plate A of the furnace is shown, together with a small section of one of the grate-bars B and transverse bearer C and a portion of the boiler-setting D. The front plate A of the furnace is, as usual, provided with a door a for the furnace and a door a' for the ash-pit.

The furnace-door is preferably of such size as to fill only the lower portion of the opening usually provided for feeding fuel to the furnace, the portion of such opening above the door a being filled or closed by plates having a fuel-opening therein through which the fuel to be handled by the feeding mechanism enters the furnace. As illustrated, the immediate opening for the admission of the fuel is formed in a plate or plates E E', bolted to the front of the furnace at the top of said door-opening, so as to be conveniently and easily removed or replaced should occasion require. The fuel-opening may be formed between the plates E E', for which purpose the upper edge of the lower plate is preferably notched, and outside of the opening so formed an evener-plate F is secured. This evener-plate forms the outlet of a chute G, through which the fuel drops by gravity or is drawn by the distributing mechanism hereinafter described, and

said evener is secured in position so as to be capable of an angular adjustment, such as will permit of directing more or less of the fuel to one side or the other of the furnace, as occasion requires. As illustrated, the evener is pivotally mounted at one end on a bolt or screw f , and at the opposite end it is adjustably connected with the plate E by a setscrew f' , working in a slot f^2 in the plate F, whereby the evener may be tipped or angularly adjusted, so as to permit the fuel to enter at the proper transverse angle to effect even distribution. Thus if it be found that more than a due proportion of the fuel is feeding to the right or left hand side of the furnace the evener is adjusted to overcome the difficulty. The chute G is usually made in two or more sections, like a stove-pipe, only flatter, so as to be easily removed or examined, and the evener may have a rim or lip to which the chute is fastened by rivets or otherwise.

Within the furnace and in position to receive the fuel passing in through the front plate is a distributor, which in the preferred construction is formed, essentially, of two distributor-plates H and H', pivotally mounted at or near their front edges and so connected as to swing vertically while maintaining their substantial parallelism, whereby the fuel entering between them may be directed toward the front or rear portion of the furnace, and thus an even distribution of the fuel from front to rear be effected. As illustrated, the distributor-plate H is provided with arms h , one at each side, which project through slots between the front plates E and E' and are provided with notches or recesses adapted to take a bearing on the edge h' of the plate E to constitute the pivotal supports for the distributor-plate. The arms h project in front of the furnace in position to coöperate with mechanical appliances for imparting the vertical oscillatory movements to the distributor-plate, and in the preferred construction the mechanical appliances consist of a pair of cams I, mounted on a power-driven shaft I', journaled in brackets i, which may be attached to or form an integral part of the front plate E'. The lower distributor-plate H' is pivotally supported by hook-shaped bearings h^2 , which coöperate with eyes or loops h^3 on the inner side of the front plate E, and the two distributor-plates H and H' are connected for simultaneous movement by a link or other suitable connection, such as indicated at K in Fig. 2, whereby when the power-driven shaft I is rotated the motion imparted to one distributor-plate will be transmitted to the other and both plates will be caused to swing in a vertical plane, as shown clearly by the full and dotted lines in the figure of the drawings last above referred to.

45 The fuel entering the furnace between the

distributer-plates is preferably projected over the grate-bars by a steam jet or jets adapted to enter the furnace at a point below the entering fuel, so as to lift the same and become thoroughly commingled therewith during the passage of the fuel and steam between the distributer-plates and during the flight of the fuel from the distributer-plates to the grate-bars or body of fuel previously deposited thereon.

In order that the fuel may be projected at a uniform angle with relation to the distributer-plates, the spreader or duct having the jet-orifices is mounted to move in unison with one of said plates, whereby the angle of projection with relation to the distributer is maintained throughout the movement, and consequently an even distribution may be maintained with a substantially uniform movement of the distributer.

As shown, the lower distributer-plate H' is provided with a fuel-supporting table H², over which the fuel travels after it first enters the distributer, and immediately around this fuel-supporting table H² is the spreader-duct for admitting steam or elastic fluid under pressure, said duct being extended from one side of the fuel-opening around said supporting-table to the opposite side. In Figs. 2 and 3 the duct is in the form of a curved pipe L, having the jet-orifices arranged so as to project the fuel radially from the fuel opening or table, as indicated by the radial lines in Fig. 3. By this arrangement of the injector-duct the fuel may be admitted through a comparatively narrow aperture or an aperture much shorter than the width of the furnace and at the same time be distributed evenly to both sides as well as to the center of the furnace. The supporting-table H² is usually cast integral with the lower distributer-plate.

Obviously it is not essential that the injector-duct should extend in a curved line, inasmuch as a substantially radial projection of the fuel from the fuel-opening may be secured by an angular arrangement of the duct, as shown, for instance, in Figs. 4 and 5, and hence I do not wish to be limited herein to the particular form of duct, although the radial arrangement of the orifices is thought to be essential.

Obviously instead of operating both plates of the distributer by connecting them together, as described said plates may be operated directly from the power connection. Thus in Figs. 6 and 7 is illustrated an arrangement wherein the lower plate H' is provided with arms M, extending through the lower front plate E' and curved upwardly, so as to be depressed by the operating-cams. In this form the arms M contact with the under sides of the arms h , and the cams operating on the arms h will cause the two plates of the distributer to be oscillated in unison and

in substantial parallelism. The distributor-plates may be varied from their parallelism by a set-screw M^2 , passing up through each of the lower arms near their ends till it bears upon the under side of the upper arms, and the plates may be held in place by suitable stops—such, for instance, as the pins m .

Obviously the operating mechanism may be made adjustable in any well-known manner in order to vary the throw of the distributor, and said distributor may be balanced by weighting the arms in front or substantially balanced in order to reduce the power required for operating the same and to permit of the use of a very small motor or engine for operating the power-shaft of a long line of furnaces.

In setting the distributor it is desirable that the two plates constituting the same should be spaced apart only a sufficient distance to permit of the effectual and ready projection of the fuel from between the same, and at their ends nearest the front of the furnace the space should be such that the action of the spreader-jet for admitting elastic fluid under pressure will create a partial vacuum, which will operate to draw the fuel in through the feed-opening and cause the same to advance over the supporting-table of the distributor into position to be acted on by the elastic fluid issuing from the jet-orifices, and herein is the office of the set-screw, as before mentioned.

To increase the effect and give direction to the fuel, ribs or flanges are formed on the plates of the distributor—as shown, for instance, at N —where the upper plate is provided with depending ribs or flanges extending forwardly, but at the same time leaving sufficient space at the sides of the distributor for the escape of fuel. If the fuel strikes the side walls of the furnace, a straighter duct or fewer side jets are used. The throw of the fuel is regulated by the steam-valve letting on more or less force. The distributor-plates may have ribs to prevent warping, if necessary.

The power-shaft I may in addition to the cam I' be provided with a pulley O , from which a belt O' may pass to a suitable elevator for raising the fuel from the bin and discharging the same into the upper end of the duct of the hoppers or chute G .

In operation the fuel fed to the hoppers passes down by gravity and is drawn into the furnace through the feed-opening in the front plate, passing thence into the distributor and forwardly over the spreader, which latter taking it on the fly through the action of the elastic fluid under pressure projects the fuel forwardly out from between the two plates of the distributor and over the grate-bars of the furnace. The movement of the distributor in a vertical plane will distribute the coal uniformly from front to rear of the

furnace, and by reason of the radial projection of the fuel by the spreader the sides of the furnace will be equally supplied.

Obviously any of the usual appliances employed for regulating the feeding of fuel from the hopper may be used in connection with the present invention, as well as any of the usual appliances for preventing the entry of air through the fuel-feeding orifice should the fuel itself fail to fill or block the passage or should such preventing be necessary.

As illustrated in the drawings, the hopper for the fuel is located some distance from the front of the furnace; but this is done in order to prevent confusion in the drawings, as in practice the hopper is brought in close to the furnace at its lower end and the connection between the hopper and the discharge-orifice correspondingly reduced in length, whereby the fuel will enter the furnace by gravity without the necessity of employing means other than the suction of the spreader for advancing the fuel. The upper end of the chute or hopper G should be braced out from the front of the boiler a short distance that the fuel may not drop perpendicularly, but slide down one side into the furnace, which the curved shape of the pipe will permit it to do.

The distributor-plates and other parts of the invention may be made any length, breadth, or shape to fit or accommodate the furnace to be equipped.

Having thus described my invention, what I claim as new, and desire to secure by Letters Patent, is—

1. In an apparatus for feeding fuel to furnaces, the combination with a distributor, movable vertically, to direct the fuel toward the front or rear of the furnace, of a fuel-supply duct opening into said distributor, a power mechanism for moving the distributor and a spreader having jet-orifices arranged to project the fuel radially from the distributor; substantially as described.

2. In an apparatus for feeding fuel to furnaces, the combination with the fuel-supply duct and spreader having jet-orifices, of a distributor having fuel-directing surfaces arranged above and below the fuel-supply duct and spreader, and mechanical means for moving said distributor in a vertical plane, to distribute the fuel from the front to the rear of the furnace; substantially as described.

3. In an apparatus for feeding fuel to furnaces, the combination with a fuel-supply duct, of a distributor having top and bottom fuel-directing surfaces, between which the supply-duct is adapted to discharge, means located between the fuel-directing surfaces for projecting the fuel from said distributor and means for imparting a vertical oscillatory movement to said distributor while the fuel is being projected therefrom for dis-

- tributing the fuel evenly from front to rear of the furnace; substantially as described.
4. In an apparatus for feeding fuel to furnaces, the combination with a fuel-supply having a duct for discharging the fuel into the furnace, of a distributor having top and bottom fuel-directing surfaces between which the fuel enters the furnace, means for projecting the fuel from the distributor embodying radially-arranged jet-orifices, and means for imparting a vertical oscillatory movement to the distributor.
5. In an apparatus for feeding fuel to furnaces, the combination with the distributor embodying top and bottom plates hinged near their forward edges to oscillate in a vertical plane and mechanical means for oscillating said plates, of a fuel-supply duct discharging between the forward edges of said plates and means located between the distributor-plates for projecting the fuel from the distributor while it is being oscillated said means embodying an elastic-fluid-discharge orifice in proximity to the lower plate and over which the fuel passes into the furnace.
6. In an apparatus for feeding fuel to furnaces, the combination with the distributor embodying top and bottom plates hinged near their forward edges to oscillate in a vertical plane and means for oscillating said distributor while maintaining the substantial parallelism of the plates, of a fuel-supply duct opening into the furnace between the forward edges of the plates and a spreader embodying discharge-orifices for an elastic fluid under pressure and movable with the distributor to maintain the angular relation between the distributor and orifices during the oscillation of the distributor.
7. In an apparatus for feeding fuel to furnaces, the combination with the distributor embodying top and bottom plates hinged near their forward edges to oscillate in a vertical plane, the lower plate embodying a fuel-supporting table, and a spreader having jet-orifices for supplying elastic fluid under pressure in proximity to the edge of said table, of means for oscillating the said distributor and a fuel-supply-discharge duct opening into said distributor between their forward edges; substantially as described.
8. In an apparatus for feeding fuel to furnaces, the combination with the distributor embodying top and bottom plates hinged near their forward edges to oscillate in a vertical plane, a lower plate embodying the fuel-
- supporting table, a spreader having jet-orifices radially arranged around said fuel-supporting table and means for oscillating said distributor, of a fuel-supply having a duct for discharging fuel between said plates and over the fuel-supporting table; substantially as described.
9. In an apparatus for feeding fuel to furnaces, the combination with the distributor embodying top and bottom plates hinged near their forward edges to oscillate in a vertical plane, a duct for supplying elastic fluid under pressure mounted on and movable with said distributor and having radially-arranged discharge-orifices, of a fuel-supply having its discharge between the outer edges of the distributor-plates; substantially as described.
10. In an apparatus for feeding fuel to furnaces, the combination with the distributor embodying top and bottom plates hinged near their forward edges to oscillate in a vertical plane in unison operating-arms projecting through the support for the plates, and means located between the plates and movable therewith for projecting the fuel from between the plates, of a power-shaft having operating-cams co-operating with said arms to oscillate the distributor, and a fuel-supply having a discharge-duct opening into the distributor between the top and bottom plates thereof; substantially as described.
11. In an apparatus for feeding fuel to furnaces, the combination with the distributor, of a fuel-supply duct and an evener having a transversely-extending discharge-aperture for admitting the fuel to the distributor and adjustable angularly to raise or lower one end of the aperture with relation to the other and thereby control the fuel fed to the sides of the furnace; substantially as described.
12. In an apparatus for feeding fuel to furnaces, the combination with the front plate, having an aperture therein and the distributor on the inner side of said plate, of a fuel-supply, and an evener, mounted on said front plate, and having an aperture therein, forming the discharge-duct of the fuel-supply said evener being adjustable to raise or lower one end of the aperture with relation to the other and thereby control the fuel fed to the sides of the furnace; substantially as described.
